US00D931939S

(12) **United States Design Patent** (10) **Patent No.:** **US D931,939 S**
(45) **Date of Patent:** **** Sep. 28, 2021**

(54) **POLE-MOUNTABLE DIGITAL BANNER**

(71) Applicant: **Duke Energy Corporation**, Charlotte, NC (US)

(72) Inventors: **James Cleveland**, Cornelius, NC (US); **Gregory S. Tribbe**, New York, NY (US); **Louis Lombardi**, Maplewood, NJ (US); **Gilbert DeFreitas**, Palm Coast, FL (US); **Shanda Hardin**, Charlotte, NC (US)

(73) Assignee: **Duke Energy Corporation**, Charlotte, NC (US)

(**) Term: **15 Years**

(21) Appl. No.: **29/682,510**

(22) Filed: **Mar. 6, 2019**

CLAIM

The ornamental design for a pole-mountable digital banner, as shown and described.

DESCRIPTION

FIG. 1 is a front perspective view of a pole-mountable digital banner, showing our new design; FIG. 2 is a rear perspective view thereof; FIG. 3 is a front view thereof; FIG. 4 is a rear view thereof; FIG. 5 is a side view thereof; FIG. 6 is an opposing side view thereof; FIG. 7 is a top view thereof; FIG. 8 is a bottom view thereof; and, FIG. 9 is a front perspective environmental view thereof. The evenly-dashed broken lines depict portions of the pole-mountable digital banner and environmental structure that

(Continued)

form no part of the claimed design. The dash-dot broken lines depict the bounds of the claimed design and form no part of the claimed design. The diagonal lines in FIGS. 1, 3, and 9 indicate a transparent protective surface over a digital display screen.
